[57] CLAIM

[21] Appl. No.: 56,757

The ornamental design for the exterior surface design of a pair of automobile doors, as shown and described.

[22] Filed: Jul. 8, 1996

DESCRIPTION

[51] LOC (6) Cl. 12-16

FIG. 1 is a side view of my exterior surface design of a pair of an automobile's doors in bold lines;

[52] U.S. Cl. D12/196

FIG. 2 is a perspective front view of my new exterior surface design of a pair of automobile doors; and,

[58] Field of Search D12/196, 90-92;
296/185, 146, 151, 152; 49/502, 503, 479

FIG. 3 is a perspective rear view of my new exterior surface design of a pair of automobile doors.

[56] References Cited

The broken lines showing of the automobile's body is for illustrative purposes only, and forms no part of my claim design.
